UNITED STATES PATENT OFFICE.

JOSEPH S. PECKER, OF PHILADELPHIA, PENNSYLVANIA.

DOUBLE-RIB-KNITTING MACHINE.

Application filed March 30, 1922. Serial No. 548,037.

To all whom it may concern:

Be it known that I, JOSEPH S. PECKER, a citizen of the United States, residing at Philadelphia, in the county of Philadelphia 5 and State of Pennsylvania, have invented new and useful Improvements in Double-Rib-Knitting Machines, of which the following is a specification.

The invention relates to a double rib 10 knitting machine.

The object of the present invention is to provide a simple, practical and efficient means of strong and durable construction for adjusting the position of the needle bar 15 so that the tips of the needles can be tilted inwardly towards the center or outwardly away from the center and positively secure in whatever position they are designed or required to occupy.

Another object of the invention is to provide means for adjusting the needle bar in 20 a horizontal direction so that the needles can be made to line up with the thread guides in any desired position.

With these and other objects in view the invention consists in the construction and novel combination and arrangement of parts hereinafter fully described, illustrated in the accompanying drawings and pointed out in 30 the claims hereto appended, it being understood that various changes in the form, proportion and minor details of construction, within the scope of the claims, may be resorted to without departing from the spirit 35 or sacrificing any of the advantages of the invention.

In the drawings, in which like characters of reference designate corresponding parts in the several views:—

Figure 1 is a side elevation, partly in section, of a knitting machine embodying 40 the present means, parts being omitted.

Figure 2 is an elevation of one end of the knitting machine.

Figure 3 is a detail sectional view on the line 3—3 of Figure 1.

Figure 4 is an enlarged detail view of one of the cradles of the needle bar.

Figure 5 is a longitudinal sectional view 50 of the same.

Figure 6 is an end view of the cradle shown in Figure 4.

Figure 7 is a detail sectional view of the angle needle bar.

55 In the accompanying drawings, in which is illustrated the preferred embodiment of

the invention, the frame of the machine comprises standards 1 and 2 tied together by horizontal cross bars or braces 3 and 4 and provided at the upper and lower portions 60 with vertically aligned guide-ways 5 for the reception of vertically reciprocating staffs 6. The upper and lower guide-ways, as explained in my application for patent, filed January 12, 1922, Serial No. 528,776, 65 are spaced apart as far as the construction of the machine will permit in order to afford a firm construction and prevent any possibility of shake or vibration of the vertically reciprocating staff 6 in the vertical motion 70 of the same at either end of the machine. The vertically reciprocating staffs carry needle bars 7 which are provided with the usual knitting needles 8 and the up and down motion is imparted to the needle bars 75 by cams 9 mounted on the main operating shaft 10 of the machine and actuating two pairs of rocking levers 11, one side being located at each end of the machine and connected by link connections 13 with the lower 80 ends of the vertically reciprocating staffs 6. The rocking levers 11 are mounted on short horizontal shafts 14, each journaled in a bearing bracket 16 extending inwardly and upwardly from the base of the frame and having inner and outer upwardly extending bearings 15 and 15^a. The rocking levers 11 are located at the inner and outer sides of the vertically reciprocating staffs, each 85 pair of vertically reciprocating staffs being 90 located between the members of a pair of rocking levers 11.

Each rocking lever 11 is provided at its inner portion with a longitudinal slot 17, in which is mounted a sliding block 18 carrying a pin or pivot 19 and adjustable longitudinally in the slot by an adjusting screw 20 journaled in the inner end of the rocking lever and threaded into the slideable pivot carrying block, as explained in the aforesaid application, whereby when the adjusting screw is rotated the slideable block will be moved inwardly and outwardly with respect to the end of the rocking lever. The link connection between each rocking lever 95 and the vertically reciprocating staff is composed of upper and lower sections 21 and 22 and a centrally connecting member 23, which is in the form of a right and left hand threaded adjusting screw. The upper and lower sections 21 and 22 are provided with threaded openings or sockets, which are en- 100 105 110

gaged by the right and left hand threaded portions of the connecting member 23 and the latter is provided with a central polygonal portion adapted to receive a wrench or 5 other suitable tool for rotating the right and left hand threaded adjusting screw or member 23 to vary the effective length of the link connection between the rocking lever and the vertically reciprocating staff. Suitable 10 lock nuts are provided for securing the adjusting screws 23 and the upper and lower sections 21 and 22 in their adjustment.

Each rocking lever 11 is provided at its outer end with a roller 25 which runs in a 15 cam groove 26 in the cam 9 and the said cam groove, which forms a track for the roller, tends to hold the lever in a firm position at any part of the cam and thereby prevents lost motion and eliminates the necessity of 20 employing spring tensions or weights to prevent such lost motion.

The needle bar 7, which is in the form of an angle bar, consists of a substantially horizontal flange or wing 7^a and an upwardly 25 extending flange or wing 7^b and is carried at each end by a pivoted bracket or cradle 27 secured to the under side of the horizontal flange of the needle bar by bolts 28, or other suitable fastening means. The pivoted 30 bracket or cradle consists of a substantially rectangular body portion and an approximately L-shaped arm 30 (see Figs. 4 and 5) extending outwardly from the body portion and laterally with respect to the needle 35 bar and forming a recess receiving the upper end of the vertically reciprocating staff 6 and bridged by a horizontal pivot 32 piercing the staff 6 and having its terminal portion mounted in a flange 33 of the body portion or pivoted bracket or cradle 27 and in 40 the arm 30. The bracket or cradle is adapted to rock on the pin or pivot 32, which is arranged horizontally and the pivotal or rocking movement enables the needle bar to 45 be adjusted so that the tips of the needles can be tilted inwardly toward the center or outwardly away from the center, as required. Also the recess 31 permits a limited 50 longitudinal adjustment of the needle bar in a horizontal direction, so that the needles can be made to line up with the thread guides in the desired position. The arm of the pivoted bracket or cradle 27 is provided at the laterally extending portion with upper and lower adjusting screws 34 and 35 55 provided with lock nuts 36 and 37 and mounted in suitable threaded openings in the said arm 30 and arranged to engage the vertically reciprocating staff. The needle bar 60 is secured in its longitudinal adjustment by means of an adjusting screw 38, provided with a lock nut 39 and mounted in a threaded opening in the laterally extending portion of the arm 30 and engaging the vertically reciprocating staff at the outer side 65

thereof. This double adjustment of the cradle or pivoted bracket 27, by means of the said adjusting screws, as clearly illustrated in Figures 4 to 6, inclusive of the drawings, enables the needle bar to be rigidly held in proper position with relation to the vertically reciprocating staffs after adjustment. The recess 31, formed by the L-shaped arm and the body portion of the cradle or pivoted bracket 27, may be varied in width to provide for the required amount of longitudinal adjustment of the needle bar and the horizontal pin or pivot which forms a fulcrum for the cradle or bracket 27 may be secured to the body portion and arm of the cradle or bracket in any desired manner.

The needle bars carry the usual knitting needles 8 and the thread or yarn guides 41 are arranged in separate blocks 42 which are carried by slides 43. The slides 43 are 75 slidably suspended from hangers 44 by horizontal rods 45 slideable in guide members 46 of the said hangers 44 and secured in openings 47 of blocks 48 by clamping screws 49. The blocks 48 are provided with reduced 80 portions 50, which are secured in openings 51 of the slides 43 by pins or keys 52. The blocks 48 are arranged in pairs and the members of each pair are spaced apart at the end portions of the slide 43. The hangers 44 are constructed substantially the same as 85 described in my co-pending application #528,775, filed January 12, 1922. The horizontal rods 45 are of sufficient length to permit the necessary longitudinal movement of 90 the slides 43.

The hangers 44 depend from a rocking shaft 53 and the slide 43 is retained in its horizontal motion by upwardly extending 95 arms 54 provided at the top with arcuate portions 57 having curved slots 58, through which extend horizontal pins 59 carried by and extending outwardly from substantially L-shaped brackets 60. The brackets, 100 which are bolted or otherwise secured to the rocking shaft 53, have depending portions through which pass the threaded inner ends 61 of the pins 59. The pins 59, which are provided at their inner ends with thumb nuts 62, are equipped with blocks 63 rectangular in cross section and fitted between and interlocked with spaced lugs or flanges 64 formed integral with and projecting from the depending portions of the bracket 60. Each block is provided with a central 105 opening 65, through which passes the horizontal pin 59 and the block is rigidly secured to the pin by a key 66 piercing the block and the pin. The spaced lugs or 110 projections 64 provide an intervening recess to receive the polygonal block 63, which is drawn into the recess and tightly clamped against the depending portion of the bracket by the thumb nut 62. The brackets are 115 located at the inner sides of the upwardly 120 reciprocating staffs. The blocks 63 are provided with a central opening 67, through which passes the horizontal pin 59 and the block is rigidly secured to the pin by a key 68 piercing the block and the pin. The spaced lugs or 125 projections 64 provide an intervening recess to receive the polygonal block 63, which is drawn into the recess and tightly clamped against the depending portion of the bracket by the thumb nut 62. The brackets are located at the inner sides of the upwardly 130

extending arms 54 and the horizontal pins 59 extend outwardly from the brackets through the curved slots 58 and are disposed longitudinally of the rocking shaft in spaced relation with the same, as clearly illustrated in Figure 1 of the drawings.

The rocking shaft is journaled in suitable bearings of the main frame and each slide 43 is connected at one end of the machine by 10 a tie or connecting rod 67 with an upwardly extending arm 68 of a bell crank lever 69 by a yoke 70 slidably mounted on the upwardly extending arm of the bell crank lever and secured in its adjustment by a clamping 15 screw 71 having a lock nut 72. The bell crank lever is fulcrumed at its angle on a rod or pivot 73, which is supported at the end by a bearing bracket 74. The other arm of the bell crank lever is arranged in a substantially horizontal position and is provided with a longitudinal slot 75 in which is slidably mounted a yoke 76 depending from the horizontal arm of the bell crank lever and carrying the roller 68^a, which is 20 adjustable along the horizontal arm of the bell crank lever by means of an adjusting screw 77 journaled at its outer portion in the outer end of the arm and having its threaded portion extending through and engaged with the yoke 76. The adjusting screw is provided with a polygonal outer end 78 and it has a collar 79 mounted on it and located at the outer end of the longitudinal slot 75. This screw is adapted to be 25 rotated by means of a wrench or other suitable tool and it provides a fine adjustment for the roller 68^a, which engages the pattern chain. The slide is moved in one direction by the bell crank lever and it is returned or 30 moved in the opposite direction by a coiled spring (not shown), as fully explained in the aforesaid application. The upper portion of the yoke 76 is provided with flat side faces to fit against the side walls of the longitudinal slot 75 and the upper end 80 of the yoke is reduced to receive a collar 81 which 35 rests upon the face of the horizontal arm of the bell crank lever at opposite sides of the slot 75, being secured to the reduced portion 40 by a cotter pin or key 82. The lower portion of the yoke is enlarged and forms shoulders 83 which fit against the lower face of the horizontal arm of the bell crank lever at opposite sides of the said slot 75. The 45 roller 68^a is mounted on a suitable pin or pivot 84 which extends across the yoke, as clearly shown in Figure 6 of the drawings.

The pattern chains are arranged on a monitor comprising end disks or sections 85, intermediate toothed plates 86 and intervening spacing plates 87. The disks or sections of the monitor are mounted on a horizontal shaft 88, the end plates being provided with hub portions 89 and having clamping screws 50 for engaging the said shaft 88 to secure

the monitor to the same. The disks or sections are connected by longitudinally disposed bolts 91, which pierce the sections at spaced points. The teeth of the disks or wheels 86 engage the pattern chains and the spacing disks or plates are provided with opposite beveled projections 92, spaced apart to provide intervening spaces or recesses 93. The teeth of the chain, engaging the disks or wheels, interlock the chain with the said disks or wheels and the said spacer or separator disks or sections and the end disks or sections act as retainer plates for the pattern chain. The separable disks or sections, comprising the monitor, are adapted to be varied in number to enable the monitor to be varied in length to provide a monitor having the required number of pattern chains. The end disks or sections 85, the intermediate toothed disks or sections 86 and the spacing disks or sections 87 are provided with keyways 97 to enable all of the sections or members of the monitor to be readily aligned on the horizontal shaft 88. The toothed disks or plates 86, which constitute sprocket members for engaging the pattern chains, are adapted to be machined by the standard equipment in present use and the construction of the monitor renders it possible to remove worn out sprocket members 86 and to 55 replace the same with new sections or members 86 without discarding the rest of the monitor.

The machine is equipped with a tension bar 94 mounted in bearing plates 95 which are bolted or otherwise secured to the frame at the ends thereof. The tension bar 94 is arranged so that one of its edges coincides with the center of the machine, as clearly illustrated in Figure 3 of the drawings, and the coinciding or inner edge of the tension bar is located in the direction in which the fabric is stripped off the needles. The tension bar is adapted to guide the goods from the needles, as near as possible in a vertical direction between the presser plates 96.

What is claimed is:—

1. A knitting machine including a frame having vertical guideways, vertically reciprocating staffs operating in the vertical guideways of the frame and located at the opposite ends of the latter and extending upwardly from the bottom of the said frame, a needle bar carried by the said staffs, rocking levers located at the ends of the frame at the bottom thereof and extending beneath and connected with the lower ends of the staffs, and means for actuating the levers.

2. A knitting machine including a frame provided at the ends with upper and lower vertically aligned guideways, vertically reciprocating staffs operating in the guideways and extending upwardly from the bottom of the frame, needle bars carried by the staffs, rocking levers arranged in pairs

at the ends of the frame at the bottom thereof and connected with the lower ends of the staffs, and means for actuating the rocking levers.

5. 3. A knitting machine including a frame having vertical guideways located at the ends of the frame, vertically reciprocating staffs operating in the guideways and extending upwardly from the bottom of the frame, 10 needle bars carried by the staffs, rocking levers arranged at the ends of the frame at the bottom thereof and located at the inner and outer faces of the staffs and extending beneath and connected with the lower ends 15 of the same, and means for actuating the rocking levers.

4. A knitting machine, including a frame, vertically reciprocating staffs arranged in pairs at the ends of the frame, rocking levers arranged in pairs and also located at the ends of the frame and extending beneath and connected with the lower ends of the staffs, short horizontal shafts forming pivots for the rocking levers, bearing brackets having inner and outer bearings for the said shafts, and means for actuating the rocking levers.

5. A knitting machine including a frame provided at its ends with upper and lower 20 vertically aligned guideways and vertically reciprocating staffs located at the ends of the frame and operating in the guideways, needle bars carried by the staffs, rocking levers arranged in pairs and located at the 25 bottom of the frame at the ends of the same, the members of the pairs of rocking levers being located at the inner and outer faces of the vertically reciprocating staffs, and cams for actuating the rocking levers.

40 6. A knitting machine, including a frame, vertically reciprocating staffs, a needle bar, and adjustable cradles mounted on the staffs and carrying the needle bar.

7. A knitting machine, including a frame, 45 vertically reciprocating staffs, a needle bar, and cradles pivotally mounted on and ad-

justably secured to the staffs and carrying the needle bar.

8. A knitting machine, including a frame, vertically reciprocating staffs, a needle bar, 50 adjustable cradles pivotally mounted on the staffs and carrying the needle bar, and means for slidably adjusting the cradles in a direction longitudinally of the needle bar.

9. A knitting machine, including a frame, 55 vertically reciprocating staffs, cradles slidably and pivotally connected to the staffs, a needle bar carried by the cradles, adjusting screws arranged in pairs for securing the cradles in their pivotal adjustment, and 60 separate adjusting screws for securing the cradles in their sliding adjustment.

10. A knitting machine, including a frame, vertically reciprocating staffs, an angle needle bar carried by the staffs, said 65 angle needle bar having an upwardly extending web or flange and provided with a substantially horizontal web or flange, and means for adjusting the needle bar with respect to the staffs.

11. A knitting machine, including a frame, vertically reciprocating staffs, a needle bar, and cradles secured to and carrying the needle bar and provided with substantially L-shaped arms embracing the staffs 75 and pivotally connected with the same.

12. A knitting machine, including a frame, vertically reciprocating staffs, an angle needle bar having an upwardly extending flange and a substantially horizontally 80 extending flange, cradles secured to the under side of the horizontal flange and provided with substantially L-shaped arms forming recesses receiving the upper ends of the staffs, horizontal pivots slidably and pivotally connecting the cradles to the staffs, 85 and means for securing the cradles in pivotal and sliding adjustment.

In testimony whereof I have hereunto set my hand.

JOSEPH S. PECKER.
